3 Claims

This invention relates to a regenerating system for a transmitted telegraph signal.

In the conventional transmission system for a telegraph signal, it is necessary that a pass band of more than W cycle/second be assured to correctly detect a transmitted telegraph signal having the highest telegraph modulation frequency ($W/2$) cycle/second. As known in the art, a wave frequency-modulated by a rectangular wave can be represented by the following equation:

$$e = \frac{2m}{\pi} \left[\frac{1}{m^2} \sin(m\pi/2) \cos \omega t + \frac{1}{m^2-1} \cos(m\pi/2) \{ \cos(\omega-p)t - \cos(\omega+p)t \} - \frac{1}{m^2-2^2} \sin(m\pi/2) \{ \cos(\omega-2p)t - \cos(\omega+2p)t \} + \dots \right]$$

where:

ω =angular velocity of the carrier wave

m =modulation index ($\Delta f/2p$)

Δf =shift frequency

p =angular velocity of the rectangular wave

In proportion to the increase of the modulation frequency ($p/2\pi$), the respective frequency spacing between adjacent spectrums of side bands components the angular velocity of which are represented by values $(\omega-p)$, $(\omega+2p)$, $(\omega-2p)$, $(\omega+2p)$ . . . increases. If the modulation frequency ($p/2\pi=W$ cycle/second) is over one half the bandwidth of the transmission channel, a spectrum of the side band components cannot be transmitted. In such a condition, the carrier frequency only is included in the transmitted wave, so that the rectangular wave transmitted cannot be regenerated in the conventional regenerating system. A telegraph signal, such as that of a 5-unit code or 7-unit code, generally includes spectrums of modulation frequency which are multiples of the frequency of the code element. Accordingly, code elements the polarity of which are alternatively changed are at first destroyed in accordance with decrease of their pass bandwidth since the frequency of a code element is the highest modulation frequency.

An object of this invention is to provide a regenerating system for a telegraph signal transmitted through a telegraph pass-band narrower than twice the highest telegraph modulation frequency of the signal.

According to the present invention there is provided a regenerating system for a transmitted telegraph signal, comprising a rectangular wave oscillator having a frequency substantially equal to the frequency of the code element of the transmitted telegraph signal, a level detector for detecting whether or not the instantaneous level of the transmitted telegraph signal exceeds a predetermined level range and for detecting the polarity of the excess level of the transmitted telegraph signal from the level range, control means for causing, only when the level detector detects that the instantaneous level does not exceed the level range, the oscillator to generate a rectangular wave having the frequency of the code element of the transmitted telegraph signal and for causing,

2

when the level detector detects that the instantaneous level exceeds the level range, the oscillator to change the polarity of the rectangular wave in accordance with the polarity of said excess level, whereby a regenerated telegraph signal is derived from the oscillator.

The novel features of this invention are set forth with particularity in the appended claims. This invention, however, as to its construction and operation together with advantages thereof, may best be understood by reference to the following description, taken in connection with the accompanying drawings in which the same or equivalent parts are designated by the same or similar reference numerals or characters, and in which:

FIG. 1 is a block diagram of an embodiment of this invention;

FIG. 2 is a connection diagram for illustrating a rectangular wave oscillator and control means of this invention; and

FIG. 3 shows waveforms for describing the operation of the circuit illustrated in FIG. 1.

Referring to FIGS. 1 and 3, the principle of this invention will first be described. The embodiment of this invention shown in FIG. 1 comprises a rectangular wave oscillator 4, a level detector (3a and 3b), and control means (5a and 5b). It is assumed that a telegraph signal V_1 (FIG. 3) of W bands is transmitted through a telegraph pass band narrower than $(W/2)$ cycle/second and that the signal is received and applied as a wave V_2 to an input terminal 1. Code elements E_3 , E_4 , E_5 , and E_{11} of the wave V_1 are modulated with a frequency $W/2$ cycle/second, and the modulated signal cannot be transmitted through the pass-band $(W/2)$ cycle/second, so that instantaneous levels of the transmitted wave V_2 corresponding to these code elements are zero as shown. The transmitted wave V_2 is applied to the level detector which is composed of, for example, a pair of trigger circuits 3a and 3b. These circuits 3a and 3b respectively have trigger levels V_a and V_b and detect whether or not the instantaneous level (e_1) of the transmitted telegraph signal V_2 exceeds a predetermined level range V_a-V_b . The transmitted wave V_2 is converted, by the trigger circuits 3a and 3b, to rectangular waves V_3 and V_4 , which are applied to the rectangular wave oscillator 4 through terminals 5a and 5b. The polarity of waves V_3 and V_4 indicates the polarity of the excess level of the wave V_2 from the range V_a-V_b ; that is, durations (t_2-t_3) , (t_6-t_8) and $(t_{14}-t_{15})$ are plus, and durations (t_0-t_1) , (t_9-t_{11}) , and $(t_{12}-t_{14})$ are minus. The frequency of the oscillator 4 is substantially equal to the frequency of the code element of the transmitted telegraph signal V_2 and is controlled by the outputs 5a and 5b of the level detector (3a and 3b). The oscillator 4 operates under the following conditions:

- (i) Only when the level detector (3a and 3b) detects that the instantaneous level (e_1) of the wave V_2 does not exceed the level range (V_a-V_b) by more than the duration T of the code element ($E_1, E_2, \dots, E_{14}, \dots$): the oscillator 4 generates a rectangular wave V_5 having the frequency ($W/2$) of the code element of the transmitted telegraph signal V_2 .
- (ii) When the level detector (3a and 3b) detects that the instantaneous level (e_1) exceeds the level range (V_a-V_b): the oscillator change the polarity of a rectangular wave (V_6) in accordance with the polarity of the excess level.

By combination of these operations (i) and (ii), a regenerated wave V_6 corresponding to the transmitted telegraph signal V_1 is derived from an output terminal 2 of the oscillator 4.

An example of the rectangular wave oscillator 4 is illustrated in FIG. 2. In this embodiment, transistors Tr_1

and Tr_2 form an astable multivibrator $4a$, together with time constant circuits each composed of a resistor (R_1 or R_2) and a capacitor (C_1 or C_2), and a bias circuit composed of a resistor R_3 and a capacitor C_3 . Terminal $2a$ (or $2b$) is the output terminal of this multivibrator $4a$ for deriving therefrom the rectangular wave V_6 . The collectors of transistors Tr_3 and Tr_4 are respectively connected to the bases (control electrodes) of the transistors Tr_1 and Tr_2 , and the emitters of the transistors Tr_3 and Tr_4 are connected to the earth (ground) potential. The resistances of the collector-to-emitter paths (PH_3 and PH_4) of the transistors Tr_3 and Tr_4 are adjusted to "low" or "high" values by applying the waves V_3 and V_4 , respectively, to terminals $5a$ and $5b$ (which are respectively connected to the bases of transistors Tr_3 and Tr_4). Accordingly, the base-to-emitter paths (PH_1 and PH_2) of the transistors Tr_1 and Tr_2 are adjusted so as to be "open" or "shorted" (particularly, through the bias circuit of R_3 and C_3) by the waves V_3 and V_4 applied to the terminals $5a$ and $5b$.

Only when both of the paths (PH_1 and PH_2) are in the "open" state, the oscillator $4a$ operates, as an astable multivibrator changing the polarity of its output, at a frequency determined by the value of the time constant circuits (R_1, C_1 and R_2, C_2). When either of the "short" states of the paths (PH_1 and PH_2) is established, the oscillation of the oscillator $4a$ stops, and the polarity of the output of the oscillator $4a$ is changed to the plus or minus state in accordance with the alternative "short" state of the path (PH_1 or PH_2).

Referring to FIG. 3, operation of the oscillator $4a$ will now be described in detail.

(1) Time interval (t_0-t_1).—The polarity of the wave V_4 only is plus, and this plus potential is applied to the terminal $5b$. Since the base of the transistor Tr_4 becomes plus, the path PH_4 of the transistor Tr_4 is established to pass through low resistance through which the base of the transistor Tr_2 is connected to earth potential. Accordingly, the transistor Tr_2 is cut off by the bias voltage across the bias circuit (R_3, C_3), and, therefore, a current (i_1) from a source (+E) flows through only the transistor Tr_1 . As a result of the potential difference across a resistance R_4 , the polarity of the output (V_6) becomes minus.

(2) Time interval (t_1-t_2).—The polarity of the wave V_4 becomes minus at the time t_1 . Because this minus voltage cuts off the transistor Tr_4 , the base potential of the transistor Tr_2 rises abruptly. In this case, since the collector potential of the transistor Tr_2 is high while the collector potential of the transistor Tr_1 is low, the current from the source (+E) surges into the transistor Tr_2 . Accordingly, the transistor Tr_2 becomes "ON," and the transistor Tr_1 is cut off ("OFF" state).

As a result of these operations, the collector potential of the transistor Tr_1 rises abruptly. Moreover, since these operations are carried out in an instant, the abrupt rise of the collector potential of the transistor Tr_1 occurs simultaneously with the transition instant (t_1) (plus to minus) of the wave V_4 .

In this time interval (t_1-t_2), the polarity of the output (V_6) is plus, which is sustained to the time t_2 because the duration (t_1 to t_2) is shorter than the time constant τ of the time constant circuits ($R_1, C_1; R_2, C_2$).

(3) Time interval (t_2-t_3).—The polarity of only the wave V_3 becomes plus at the time t_2 . This plus potential is applied to the terminal $5a$ and makes the resistance of path PH_3 low. This low resistance causes the transistor Tr_1 to be cut off. However, the output potential V_6 is not changed since the transistor Tr_1 has been cut off at the time t_1 .

(4) Time t_3 .—The polarity of the wave V_3 becomes minus at the time t_3 . Because this minus voltage cuts off the transistor Tr_3 , the base potential of the transistor Tr_1 rises abruptly. In this case, since the collector potential of the transistor Tr_1 is high while the collector potential

of the transistor Tr_2 is low, the current from the source (+E) surges into the transistor Tr_1 .

Accordingly, the transistor Tr_1 becomes "ON," and the transistor Tr_2 is cut off ("OFF" state). As a result of these operations, the collector potential of the transistor Tr_1 drops in an instant simultaneously with the termination instant (t_3) of the plus potential of the wave V_3 .

(5) Time interval (t_3-t_6).—In this interval, both of the outputs (V_3 and V_4) are minus. These minus potentials cause the resistances of the paths PH_3 and PH_4 to be high, so that the oscillator $4a$ operates as an astable multivibrator and generates a rectangular wave V_5 , the period of which is proportional to the sum of time constants C_1, R_1 and C_2, R_2 .

(6) Time interval (t_6-t_8).—At the time t_6 , the polarity of the wave V_3 changes to plus, so that the path PH_3 assumes low resistance. Accordingly, the transistor Tr_1 is cut off, and the transistor Tr_2 becomes "ON." As a result of this operation, the output (V_6) assumes plus polarity which is sustained from the time t_6 to a time t_8 . In this period (t_6-t_8), the oscillation of the oscillator $4a$ stops. At the time t_8 , the "ON" state is switched from the transistor Tr_2 to the transistor Tr_1 as described with respect to the time t_3 .

(7) Time interval (t_8-t_9).—The operation during this period is the same as that of the period (t_1-t_2).

(8) Time t_9 .—The polarity of only the wave V_4 becomes plus at the time t_9 . This plus potential is applied to the terminal $5b$ and makes the resistance of path PH_4 low. This low resistance causes the transistor Tr_2 to be cut off. However, the output V_6 is not changed since the transistor Tr_2 has been cut off at the time t_8 . This state continues from the time t_8 to the time t_{11} .

(9) Time t_{11} .—

At time t_{11} , since the polarity of the wave V_4 becomes minus, the transistor Tr_4 assumes the "OFF" state, and the path PH_4 assumes high resistance. As a result of this operation, the base potential of the transistor Tr_2 rises abruptly, whereby a current i_2 surges into the transistor Tr_2 . Accordingly, the "ON" state is transferred from the transistor Tr_1 to the transistor Tr_2 . This state continues until a time t_{12} .

(10) Time t_{12} .—

(i) when the duration t_{11} to t_{12} is equal to or less than the duration T : simultaneously with the transition of the wave V_4 from minus to plus, the "ON" state is switched from the transistor Tr_2 to the transistor Tr_1 .
(ii) When the duration from the time t_{11} to transition instant t_{12} is greater than the duration T : in the duration t_{11} to t_{12a} , the oscillator $4a$ operates as an astable multivibrator. Accordingly, the "ON" state switches, at a time t_{12} corresponding to the transition instant of the oscillator $4a$, from the transistor Tr_2 to the transistor Tr_1 . At a time t_{12a} , the polarity of the output (V_6) of the oscillator $4a$ does not change.

(11) Time interval ($t_{12}-t_{14}$).—The operation in this period is the same as that in the period (t_6-t_{11}).

(12) Time interval ($t_{14}-t_{15}$).—The operation in this period is the same as that in the period (t_1-t_2).

(13) Time t_{15} .—The operation in this period is the same as that in the period (t_2-t_3).

According to the system of this invention, since a transmitted telegraph signal, which has not been regeneratable in the conventional art, due to distortion or destruction of its waveform, can be completely regenerated, it is possible to transmit, through a limited telegraph pass band, a telegraph signal modulated with a frequency which is more than twice the modulation frequency in a conventional system. In other words, a telegraph signal transmitted through a telegraph pass band of less than half of the essential width for a conventional system can be completely regenerated by the regenerating system of this invention. The resulting economical transmission of telegraph signals is an important feature of this invention.

The level range can be established in any zone, for example plus voltage zone or minus voltage zone, if suitable.

A telegraph signal transmitted through any transmission system as well as transmission by frequency modulation, for example transmission by amplitude modulation or D-C transmission, can be completely regenerated by the regeneration system of this invention.

What I claim is:

1. A regenerating system for a transmitted telegraph signal, comprising an oscillator for generating a rectangular wave having a frequency substantially equal to the frequency of the code element of the transmitted telegraph signal; a level detector for detecting whether or not the instantaneous level of the transmitted telegraph signal exceeds a predetermined level range and for detecting the polarity of the excess level of the transmitted telegraph signal from the level range; control means for causing, only when the level detector detects that the instantaneous level does not exceed the level range, the oscillator to generate the rectangular wave having the frequency of the code element of the transmitted telegraph signal and for causing, when the level detector detects that the instantaneous level exceeds the level range, the oscillator to change the polarity of the rectangular wave in accordance with the polarity of said excess level, whereby a regenerated telegraph signal is derived from the oscillator.

2. A system according to claim 1, in which the oscillator is composed of an astable multivibrator, and the control means is composed of a pair of controllable impedances which are respectively connected to control electrodes of active elements of the astable multivibrator, said pair of controllable impedances being controlled by the level detector.

3. A system according to claim 2, in which the astable multivibrator is composed of a pair of transistors and said control means is composed of a pair of transistors the collector-to-emitter paths of which respectively form said controllable impedances controlled by their base potentials.
